UNITED STATES PATENT OFFICE

HERMON G. WEINLAND, OF SPRINGFIELD, OHIO, ASSIGNOR TO THE SAFETY GRINDING WHEEL AND MACHINE COMPANY, OF SPRINGFIELD, OHIO, A CORPORATION OF OHIO

GRINDING MACHINE

Application filed December 10, 1927. Serial No. 239,170.

This invention relates to grinding machines, it more particularly relating to dust collectors for such machines.

The object of my invention is to provide for adjusting the receiving end of the collector relatively to the grinding wheel to thereby adapt the collector to different conditions of work performed by the wheel to more effectively collect the dust.

10 In the accompanying drawings:

Fig. 1 is a top plan view of a machine embodying the improvements.

Fig. 2 is a side elevation of the same.

15 Fig. 3 is an enlarged top plan view of the dust collector.

Fig. 4 is an enlarged side elevation of the same.

Fig. 5 is a front elevation of the same.

20 The grinding machine shown in the drawings is of the portable type which is pivotally suspended from a suitable support so that the machine can be swung to different points relatively to the work. Referring to the drawings, 1 represents a longitudinal tubular

25 main support for the parts. There is connected to the rear end of this support the casing 2 of an electric motor and attached to the forward end of the support is a cross-head 3 provided with an integrally formed bearing 4 for the shaft 5 of a grinding wheel 6.

30 This grinding wheel is driven from the motor through the medium of a belt 7, which is driven from the motor shaft (not shown) and passes about a pulley 8 on the grinding wheel shaft 5. The belt is covered by a casing 9 and the grinding wheel is protected by a hood 10.

35 There is also connected to the support 1 a hanger 11 by which the machine may be pivotally suspended by a link (not shown) from any suitable point, this hanger being adjustably secured to the support at the proper point to give the desired degree of balance.

40 The dust collector proper is indicated at 12 and it consists of an elongated hollow body of sheet metal open at both ends with its for-

ward end arranged adjacent the grinding wheel 6 and its rear end connected with a flexible tube 13 which in turn is connected with a suitable suction device (not shown). The forward end of the collector 12 is provided 50 with an adjustable mouth piece 14 which is held in different positions of adjustment by thumb screws 15 threaded on bolts 16 carried by the collector and extending through slotted openings 17 in the mouth 55 piece.

In the operation of grinding machines of this type the grinding wheel engages the work sometimes on one side of the vertical center thereof and sometimes on the other side, depending on the center of the casting which is being ground. As the dust from the wheel is thrown by centrifugal force tangentially it is obvious that this dust will take different courses depending upon which portion of the 60 wheel is performing the abrasive action upon the work. In order to adapt the collector to these varying conditions, there is provided means for adjusting the receiving end of the collector with relation to the wheel and to 65 that end the collector is supported in the following manner: Attached to the support 1 is a bracket 18, the bracket being clamped to the support by a clamping member 19 secured in position by the bolts 20. Projecting 70 laterally from the bracket 18 is a stud 21 upon which is pivotally mounted a lever 22; the lever being held in frictional engagement with the face of the bracket by a coil spring 23 which is interposed between the lever and 75 a nut 24 threaded on the end of the stud, a lock nut 25 being preferably employed to keep the nut 24 from turning. The lower end of the lever 22 is bent laterally and secured to the collector 12. Pivoted to the upper end of the lever 22 is a forwardly extending rod 26 which projects to within 80 convenient reach of the operator, this rod extending loosely through a keeper 27 secured to one of the handle bars 28 of the machine. 85

To pivot the rod to the lever, the rod is formed with an eye 26' to receive the bolt 30 carried by the lever.

By this arrangement the operator may readily position the receiving end of the collector relatively to the grinding wheel so as to insure all of the dust being collected, regardless of the nature of the work upon which the wheel is operating. When the operator swings the machine by grasping the handle 29 to vary the position of the grinding wheel relatively to the work he at the same time by manipulating the rod 26 may swing the lever 22 so as to position the receiving end of the collector either as shown in full lines or dotted lines in Fig. 2 or in any intermediate point therebetween.

It will be noticed that the handle bar 28 is extended rearwardly so as to lie alongside of the dust collector to thereby form a protecting guard for same.

Having thus described my invention, I claim:

1. In a grinding machine, a support, a grinding wheel and operating mechanism for the same mounted on said support, a hollow body forming a dust collector movably mounted upon said support with its receiving end adjacent said wheel, and manually operated means for adjusting said hollow body to alter the position of the receiving end thereof with relation to said wheel.

2. In a grinding machine, a support, a grinding wheel and operating mechanism therefor carried by said support, a hollow body forming a dust collector pivotally connected with said support with the receiving end thereof adjacent the lower portion of said wheel, and means for manually swinging said hollow body about its pivotal connection with said support to alter the position of the receiving end of said body relatively to said wheel.

3. In a grinding machine, a grinding wheel, a dust collector having its receiving end arranged adjacent to said wheel, a pivoted support for said collector, and an operating rod connected with said pivotal support and extending to within convenient reach of the operator.

4. In a grinding machine, a support, a grinding wheel and operating devices for the same carried by said support, a hollow body forming a dust collector pivotally mounted upon said support with its receiving end adjacent said wheel, manually operated means for swinging said body about its pivotal connection to alter the position of its receiving end with relation to said wheel, and a flexible tube connected with the discharge end of said body.

5. In a grinding machine, a suspended movable support, a grinding wheel and operating devices for same carried by said support, a hood for said wheel open on its under

side, a hollow body movably connected with said support forming a dust collector and having its receiving end adjacent the exposed part of said wheel, a flexible tube connected with the discharge end of said body, and manually operated means for adjusting the position of said body with relation to said support to alter the position of the receiving end thereof relatively to said wheel.

6. In a grinding machine, a movable support, a grinding wheel and operating devices for same carried by said support, a hood for said wheel open on its under side, a hollow body forming a dust collector movably connected with said support with its receiving end adjacent said wheel, an adjustable mouth piece carried by the receiving end of said body, and means for manually moving said body with relation to said support to alter the position of the receiving end thereof relatively to said wheel.

7. In a grinding machine, a pivotally suspended support, a motor mounted on one end of said support, a grinding wheel mounted at the other end of said support, a hood for said wheel open at its lower side, a hollow body forming a dust collector movably connected with said support with its receiving and adjacent said wheel, a pivoted mouth piece connected with the receiving end of said hollow body, a flexible tube connected with the discharge end of said body, and manually operated means for altering the position of the receiving end of said body with relation to said wheel.

8. In a grinding machine, a pivotally suspended main support, a motor mounted at one end of said support, a grinding wheel mounted at the other end of said support, a hood for said wheel open at its lower side, a dust collector having its receiving end adjacent the exposed part of said wheel, an adjustable mouth piece on the receiving end of said collector, a pivoted support for said collector mounted on said main support, and manually operated means connected with said collector support for adjusting the receiving end of said dust collector relatively to said wheel.

9. In a grinding machine, a pivotally suspended main support, a grinding wheel and operating mechanism for the same carried by said support, a hood for said wheel open at its lower side, a lever pivotally connected with said support, a hollow body forming a dust collector connected with one end of said lever with its receiving end adjacent the lower side of said wheel, a rod connected with the other end of said lever extending to a point within convenient reach of the operator for adjusting the receiving end of said body with relation to said wheel, yieldable means for holding said lever in different positions of adjustment, and a flexible tube connected with the discharge end of said body.

10. In a grinding machine, a suspended movable support, a grinding wheel and operating devices for same carried by said support, a hood for said wheel open on its under

10. In a portable grinding machine, a support, a grinding wheel carried by said support, a hood for said grinding wheel open at its under side, a dust collecting body mov-
5 ably connected with said support and ar-
ranged at one side thereof with its receiv-
ing end adjacent said wheel, and an operating
handle having a bar connected with said sup-
port, said bar being arranged to form a guard
for said hollow body.

10 In testimony whereof, I have hereunto set
my hand this 6th day of December, 1927.

HERMON G. WEINLAND.
